LUMBER STACKER

John Knudson, Libby, Mont.

Application November 11, 1933, Serial No. 697,664

8 Claims. (Cl. 214—16)

This invention relates to a lumber stacker, mainly designed for stacking lumber on a car which is to be moved into a kiln, the general object of the invention being to provide means for feeding the lumber to the stack and placing strips between the layers of lumber and in such a manner that the lumber can be easily and quickly stacked with the minimum amount of labor.

10 This invention also consists in certain other features of construction and in the combination and arrangement of the several parts, to be hereinafter fully described, illustrated in the accompanying drawings and specifically pointed out in the appended claims.

15 In describing the invention in detail, reference will be had to the accompanying drawings wherein like characters denote like or corresponding parts throughout the several views, and in which:—

20 Figure 1 is an elevation of the invention showing the same associated with a car on which the lumber is stacked and with the car moved vertically by hydraulic means.

25 Figure 2 is a top plan view of the invention.

Figure 3 is a fragmentary top plan view with the carriage in its rearmost position and with the strip holding means removed.

30 Figure 4 is a section on line 4—4 of Figure 2.

Figure 5 is a section on line 5—5 of Figure 2.

Figure 6 is a rear end view.

Figure 7 is a section on line 7—7 of Figure 3.

Figure 8 is a sectional detail view showing 35 the finger carrying shaft and one of the fingers thereof for holding the lumber from return movement after being placed on the stack.

Figure 9 is a view of the bar operated by the movement of the carriage for rocking said finger carrying shaft.

Figure 10 is a view of said shaft.

Figure 11 is a view of the end member to which the rear ends of the tracks are connected and which carries the rear shaft for the upper reach 45 of the endless members.

Figure 12 is a plan view showing how one section of a track member is hinged to the other section.

Figure 13 is a section on line 13—13 of Figure 50 12.

Figure 14 is a section on line 14—14 of Figure 12.

Figure 15 is a fragmentary vertical sectional view, the section being taken through Figure 11 55 and this figure also shows a portion of the lever for raising and lowering the rear end of the tracks.

Figure 16 is a fragmentary top plan view of the rear end of one of the track members and a part 60 of the cross piece shown in Figure 11.

Figure 17 is a fragmentary sectional view through one of the track members and showing one of the sprocket wheels.

Figure 18 is a view showing the clutch means for the drive of the disk which operates the carriage.

Figure 19 is a section on line 19—19 of Figure 18.

Figure 20 is a section on line 20—20 of Figure 18.

Figure 21 is a sectional view through the cylinder.

Figure 22 is a top plan view of the frame for holding and depositing the strips.

Figure 23 is a section on line 23—23 of Figure 22.

Figure 24 is a bottom plan view of one of the strip holders.

Figure 25 is a section on line 25—25 of Figure 24.

Figure 26 is a section on line 26—26 of Figure 23.

Figure 27 is a view of one of the latch members for holding the rear end of a strip.

Figure 28 is a view of the carriage operated 25 for operating the strip release bar.

Figure 29 is a view of one of the combined release and knife members.

Figure 30 is a plan view of the carriage.

Figure 31 is a view of the shaft and its associated parts for operating the levers which raise 30 and lower the rear ends of the track members.

Figure 32 is a sectional view through the valve.

Figure 33 is a view of the lever for operating the members which deposit the lumber upon the endless members.

Figure 34 is a top plan view showing how the strips are placed on a layer of lumber on the stack.

Figure 35 is a view of one of the strips.

In these drawings, the latter A indicates a horizontally arranged frame of openwork construction and supported by the legs *a* and on the top of this frame are arranged the pair of parallel longitudinally extending track members 1, each of which has a rear part 1' hinged thereto for vertical swinging movement, as shown at 2. Endless members 3, preferably made in the form of chains, pass through grooves formed in the upper faces of these track members, and these members pass over the upper sprockets 4 carried by the front and rear shafts 5 and over the sprockets 6 carried by the front and rear shafts 7, these shafts being carried by the hangers 8 carried by the front and rear ends of the frame at 45 the lower part thereof. Thus each endless member or chain moves in a rectangular path with the upper reach thereof passing through the groove in a track member so that these endless members will move lumber from the front of the frame to the rear thereof.

50

Figure 15 is a fragmentary vertical sectional view, the section being taken through Figure 11 55 and this figure also shows a portion of the lever for raising and lowering the rear end of the tracks.

Figure 16 is a fragmentary top plan view of the rear end of one of the track members and a part 60 of the cross piece shown in Figure 11.

65

The lumber to be stacked is placed by hand on the pair of supporting beams 9 which are fastened to the ends of a shaft 10 supported for rocking movement in the forward part of the frame, and 5 each member is arranged adjacent the outer side of each endless member and each member or beam 9 is attached to the shaft 10 at a point slightly in rear of the center of the beam. Each beam has a projection 11 extending upwardly 10 therefrom, adjacent each end thereof, the rear projections preventing the lumber from passing off the beams until said beams are tilted by a hand lever 12 pivoted intermediate its ends to a side of the frame and having its rear end bent 15 at right angles, as shown at 13 in Figure 33, to pass under the forward end of one of the beams 9, as shown in Figure 2. Thus by depressing the handle part of this lever, the two beams are tilted so that the rear projections 11 pass below 20 the track bars 1 and thus the endless members can move the lumber, which has been placed in a layer on the beams, toward the rear end of the frame. An upright board 14 is fastened to the frame, at one side thereof, and acts as a gauge 25 for the ends of the lumber as it is placed on the beams 9.

When the lumber reaches the rear end of the frame, the first piece strikes a pivoted finger 15 at the rear end of the frame forces the same outwardly and downwardly, which exerts a pull on the rod 16, see Figure 7, and as this rod is connected with the plug 17 of a valve 18 placed in a conduit 20 leading from a source of fluid under pressure to a cylinder 21, the fluid enters the cylinder and moves a piston 22 therein and thus causes the piston rod 23 to swing forwardly a hinged post 24 against the action of a spring 25 so as to move the post out of contact with a projection 26 on a disk 27 attached to the upper end 30 of a vertical shaft 28 journaled in the frame. The post 24 is hinged to a lever 29 pivoted intermediate its end to a bracket 30 attached to a lower part of the frame and the forward end of this lever is connected by a link 31 to a clutch 35 shifting lever 32 for sliding the clutch part 33, on a shaft section 34, into and out of engagement with the spring actuated clutch arms 35 which are adapted to engage recesses 36 in the section 34. These arms are carried by a tubular part 37 attached to a shaft section 38 which is driven by means hereinafter to be described. The section 34 carries a pinion 39 which meshes with the gear 40 on the lower end of the shaft 28 which carries the disk 27. A spring 41 connects the lever 29 with a part of the frame and tends to move the parts to a position to engage the clutch members so that when the post 24 is moved by the operation of the piston in cylinder 21, out of engagement with the projection 26 of the disk 27, the spring 41 moves the lever 29 to a position which will cause the link 31 and the lever 32 to operate the clutch parts and thus connect the disk 27 with the driven shaft 38 so that the disk will be rotated.

60 The first part of the movement of the disk 27 will cause a projection 42 thereon to engage the upright part 43 of a sliding bar 44 so that this bar is moved forwardly and this results in a rocking movement of the shaft 45 to which the bar is connected by the arm 46 and said shaft has the arms 47 thereon, see Figure 31, for engaging the forward ends of levers 48 pivoted at 49, and this rocking movement of the shaft 45 moves the arms 47 out of engagement with the levers, which have 75 their rear ends pivoted to the depending mem-

bers 51 of the cross piece 50 to which the rear ends of the track sections 1 are connected. Thus as the arms 47 move out of engagement with the forward ends of the levers 48, the weight of the parts will cause the track sections 1 and the parts associated therewith to move downwardly and as the forward ends of the levers 48 move upwardly, the vertically arranged stop bars 53 connected at their lower ends with the levers 48, will have their upper ends moved above the track sections and the upper reaches of the endless members, so that these bars 53 will act as stop members to prevent another load of lumber deposited upon the endless members by the tilting of the beams 9, from moving rearwardly with the first lumber deposited upon the endless members. The rear upper shaft 54 which carries the sprockets 4' for the endless members is also carried by this member 50 and downward movement of the parts is limited by the stop members 54 attached to the cross piece 50, engaging the upper end of the rear part 55 of the frame.

As the rear ends of the track sections move downwardly, the lumber will be deposited upon the fingers 57 of a carriage 58 slidably arranged in the frame and said fingers have the upstanding projections 59 intermediate their ends for causing the lumber to move with the carriage. The carriage is provided with a tongue 60 to which the rear end of a pitman 61 is pivoted, the front end of the pitman being pivoted at 62 to the projection 26 of the disk 27.

As will be seen, the carriage moves the lumber beyond the rear end of the frame and during the rearward movement of the carriage a projection 63 thereon engages a shoulder 64 on a sliding bar 65 supported on the frame by the guides 66 so that the bar is moved by the carriage and the rear end of the bar is connected by a link 68 with the bent end of a shaft 67 journaled in the rear part of the frame and provided with the fingers 68, see Figures 8 and 10. Thus the shaft 67 is rocked to a position where the fingers will be substantially vertical and these fingers act to prevent the lumber on the fingers 68 of the carriage from returning with the carriage as the carriage returns to its normal position. Thus these fingers will push the lumber off the carriage and upon the stack. On the return movement of the carriage, the projection 63 strikes another shoulder 69 on the bar 65, which returns the parts to normal position, with the fingers 68 in lowered position and fitting in recesses 70 in the rear part of the frame, as shown in Figure 8.

As the carriage nears its rear limit of movement, a part thereon strikes a block 52 on a bar 52 which is pivoted at its front end to an arm 53 on the shaft 49 so that the bar 52 is moved rearwardly and this movement returns the shaft 45 to the position shown in Figure 4, with the arms 47 depressing the levers 48 so that the stop members 53 are lowered and the rear ends of the track sections raised. A guide 56 is provided for the bar 52.

When the finger 15 has been released by the lumber, a spring 71 connected to the arm of the valve returns the parts to normal position and in this normal position the plug 17 is moved to the position shown in Figure 32, so that the supply pipe 20 is closed and the cylinder is in communication with the atmosphere. When this takes place, the spring 25 returns the post 24 to upright position and moves the piston to its normal position in the cylinder, as shown in Figure 75

21, and as the projection 26 of the disk 27 strikes the post 24 near the end of the revolution of the disk, the lever 29 is returned to its normal position, shown in Figure 2, against the action of the spring 41, so that the clutch is moved to releasing position and the parts come to rest in the position they occupy in Figure 2.

A motor M is supported on the frame and its shaft is operatively connected to the section shaft 38, such as by the chain and sprockets shown generally at 73 in Figure 1, and said shaft 38 carries a pulley 74 over which a belt 75 passes, said belt also passing over a pulley 76 on the upper sprocket carrying shaft 5' at the rear of the frame and as this shaft is the one which is carried by the movable part 50, it will be seen that the drive of the endless members will not be interfered with by the up and down movement of the rear ends of the track members and endless members.

A frame B is supported from the rear end of the main frame A and projects beyond said rear end and includes the long rear uprights 78 in which are rotatably supported the lower shaft 79 and the upper shaft 80. The lower shaft carries the drums 81 and this shaft is rotated by means of a crank handle 82 and is held in adjusted position by the ratchet means 83. Cables 84 are wound on the drums and pass over the pulleys 85 on the shaft 80 and these cables are connected to the front end of a tiltable frame 86, see Figure 22, which has trunnions 87 at the rear ends of its side pieces which fit in the vertically arranged slotted brackets 88 carried by the uprights 78, see Figure 6. The rear end of the frame 86 may be adjusted vertically through means of a hand lever 89 pivoted to a depending part 90 at the rear end of the frame 86 and held in adjusted position by the sector 91. Thus this frame 86 can be raised and lowered and have its inclination adjusted by means of the lever 89 and the cables and drums.

Front and rear pieces of this frame 86 are formed with the notches 92 in their upper edges for receiving the ends of the holders 93 for holding the strips which are used to space the layers of lumber in the stack. Each of these holders is formed of a pair of side pieces 93' and the front and rear end pieces 93'', these parts forming a chamber for receiving the strips and, as shown in Figure 25, the side pieces are extended beyond the front end to engage a notch in the front ends of the frame 86. The end pieces 93'' are beveled, as shown in Figure 25, to facilitate placing of the strips in the holder. A pair of spring actuated latch members 94 is arranged adjacent the rear end piece 93'' and one of these latch members is shown in Figure 27. As will be seen, the front bent ends of these latch members extend across the bottom of the chamber formed by the holder to support the rear ends of the strips placed therein. These latch members are connected together by a spring 95 which holds the latch members in holding position.

To the lower edge of the front end piece 93'' of each holder is pivoted a combined holding member and knife 96, shown in Figure 29. This member includes the substantially Z-shaped arm 97 having a notch 98 in its upper end, the holder part 99 and the beveled member or knife 100. The holder part normally extends into the front end of the chamber of the holder and supports the front end of a strip placed therein.

A bar 101 is slidably arranged in the front part 75 of the frame 86 and carries the pins 102 for

engaging the slots or notches 98 in the parts 97 of the members 96 so that reciprocatory movement of this bar will operate the members 96.

A bell crank 103 is pivoted to an upright 104 on the rear of the main frame A and this bell crank is connected to one end of the bar 101 by a pin 105 on the end of the bar 101 engaging a slot 106 in the bell crank. A bar 107, shown in Figure 28, is pivoted to the bell crank and passes through an opening in the upper end of an upright 108 attached to the carriage and said bar is formed with the projections 109 spaced apart and engaged by the upright 108 so that the bar is moved by the carriage when the same nears either limit of its movement.

Thus it will be seen that the strips used for separating the layers of lumber are placed in the holders and that different numbers of these holders can be used, according to the number of strips to be used and the holders can be adjusted 20 in the frame by providing a plurality of the notches 92. As the carriage moves rearwardly, the upright 108 thereon will engage the rearmost projection 109 on the bar 107 so that the bar 25 operates the bell crank 103 and shifts the bar 101 so that the holders 99 of the members 96 are moved from under the front ends of the strips placed in the holder members 93 and thus the front ends of the strips will drop upon the top of the stack and before the front end of a strip is 30 released by the member 99, the knife 100 passes between the front end of the lowermost strip and the next strip so that this knife acts to hold the second strip from the bottom in the holder 35 as the front end of the bottom strip drops therefrom. On the reverse movement of the member 96, the member 99 moves to a position to catch the front end of a strip before the knife 100 releases said end of said strip. As the rear 40 ends of the strips are still held by the latch members 94, the strips will assume an inclined position, as shown by 110 in Figure 1, so that the new layer of lumber being placed on the stack by the carriage will move up the strips and as soon as the weight of the lumber on the sticks is greater 45 than the resistance of the springs 95, the latch members will open and permit the rear ends of the strips to drop upon the stack and thus the new layer of lumber will rest on these sticks and be spaced from the next layer below.

Figure 1 shows the stack of lumber L placed on a car X which is moved vertically off the track T by hydraulic means shown generally at H. The hydraulic means can be controlled in any manner to properly adjust the stack to receive 55 the layer of lumber from the stacker thereon. Figure 34 shows a layer of lumber with the strips 110 thereon and Figure 35 shows one of these strips.

I prefer to have the endless members travel 60 about one-tenth faster than the carriage.

It is thought from the foregoing description that the advantages and novel features of the invention will be readily apparent.

It is to be understood that changes may be made in the construction and in the combination and arrangement of the several parts, provided that such changes fall within the scope of the appended claims.

What is claimed is:—

1. A lumber stacking apparatus comprising a frame, endless members carried by the frame, manually operated means for placing on said endless members a number of boards, a reciprocatory carriage carried by the frame, means for lower-

- ing the rear positions of the endless members to deposit the lumber thereon upon the carriage, means for removing the lumber from the carriage on the return movement of the carriage, means for reciprocating the carriage, and means associated with the reciprocating means for lowering and raising the rear portions of the endless members, spacer strip holders, and means operated by the movement of the carriage for releasing the strips from the holders and placing them on the stack in advance of the lumber placed on the stack by the carriage.
2. A lumber stacker comprising a frame, endless members supported by the frame, a tiltable carrier on which a number of boards are placed by hand, manually operated means for tilting the carrier to deposit the boards upon the endless members, a reciprocatory carriage in the frame, means for lowering portions of the endless members to deposit the boards upon the carriage, said carriage having its board receiving portion moving beyond the frame on the delivery stroke of the carriage, means operated by the carriage for moving the boards off the carriage on the return stroke of the carriage, means for operating the carriage.
3. A stacker of the class described comprising a frame, endless members supported thereby, manually operated means for depositing the lumber upon the endless members, a reciprocatory carriage in the frame, track means for the endless members including movable rear parts, means for normally holding said movable parts in raised position with the endless members carried thereby above the carriage, means for releasing said holding means to permit the movable track portions to move downwardly to deposit lumber upon the carriage, means for reciprocating the carriage, including a disk and a pitman connecting the disk with the carriage, and means on the disk for moving the said holding means to releasing position.
4. A stacker of the class described comprising a frame, endless members supported thereby, manually operated means for depositing the lumber upon the endless members, a reciprocatory carriage in the frame, track means for the endless members including movable rear parts, means for normally holding said movable parts in raised position with the endless members carried thereby above the carriage, means for releasing said holding means to permit the movable track portions to move downwardly to deposit lumber upon the carriage, means for reciprocating the carriage, including a disk, a pitman connecting the disk with the carriage, and means on the disk for moving the said holding means to releasing position, and means for rendering the disk operating means active when the lumber nears its discharging point.
5. In combination with an adjustable lumber stack holding member, lumber feeding means for placing the lumber in superimposed layers on said member, such means including a reciprocatory carriage, a frame supported above the stack, holders adjustably arranged in the frame, each holder comprising a chamber for receiving a separator strip, spring actuated members for holding the rear ends of the strips in the chambers, means for holding the front ends of the strips in the front ends of the chambers, and means operated by the carriage for moving said last mentioned holding means to releasing position.
6. In combination with an adjustable lumber stack holding member, lumber feeding means for
- placing the lumber in superimposed layers on said member, such means including a reciprocatory carriage, a frame supported above the stack, holders adjustably arranged in the frame, each holder comprising a chamber for receiving a separator strip, spring actuated members for holding the rear ends of the strips in the chambers, means for holding the front ends of the strips in the front ends of the chambers, and means operated by the carriage for moving said last mentioned holding means to releasing position, such last mentioned holding means including a lower part forming a rest for the front end of the lowermost strip and an upper beveled member for passing between the front ends of the lowermost strip and the next strip above as the lower member is moving to position to release the front end of the lowermost strip.
7. In combination with an adjustable lumber stack holding member, lumber feeding means for placing the lumber in superimposed layers on said member, such means including a reciprocatory carriage, a frame supported above the stack, holders adjustably arranged in the frame, each holder comprising a chamber for receiving separator strips, spring actuated members for holding the rear ends of the strips in the chambers, means for holding the front ends of the strips in the front ends of the chambers, means operated by the carriage for moving said last mentioned holding means to releasing position, and means for adjusting the holder frame vertically and as to its inclination.
8. A lumber stacker comprising a supporting frame, track members at the top of the frame, each track member including a rear part hingedly connected to the front part, endless members supported in the frame and having their upper reaches passing over the track members, a lever supported in the frame and connected with the rear ends of the hinged track sections, a rock shaft journaled in the frame, an arm thereon engaging a part of the lever to hold the same in position with the track sections in raised position, a bar connected with the rock shaft, a disk rotatably supported in the frame and having a projection thereon for engaging a part of the bar to move the same to rock the shaft to move the arm out of engagement with the lever, a stop projection on the lever which, when the lever is in raised position, will extend above the tracks, a carriage supported in the frame, means for reciprocating the same by the rotary movement of the disk, said carriage receiving lumber from the endless members when the hinged track sections are in lowered position, means operated by the carriage when the same nears the end of its rearward stroke for returning the rock shaft to its normal position to cause the arm on the rock shaft to lower the front end of the lever to raise the track sections, a drive shaft, clutch means for connecting the same to the disk, means operated by the lumber near its discharge position for moving the clutch means into operative position to rotate the disk, manually operated means for depositing a number of boards on the endless members to form the successive layers of a stack, a finger carrying shaft at the rear of the frame, the fingers of which prevent the lumber from returning with the carriage after being placed over the stack, means for operating the shaft by the movement of the carriage, and means operated by the movement of the carriage for depositing spacer strips on the stack between the layers of lumber.
